United States Patent Office.

JOSEPH C. CURRYER AND WILLIAM C. YOUNG, OF THORNTOWN,
INDIANA.

Letters Patent No. 92,280, dated July 6, 1869.

IMPROVEMENT IN DOOR-LATCHES.

The Schedule referred to in these Letters Patent and making part of the same.

To all whom it may concern:

Be it known that we, JOSEPH C. CURRYER and WILLIAM C. YOUNG, of Thorntown, in the county of Boone, and State of Indiana, have invented a new and valuable Improvement in Latch-Fastenings; and we do hereby declare that the following is a full, clear, and exact description of the construction and operation of the same, reference being had to the annexed drawings, making a part of this specification, and to the letters and figures of reference marked thereon.

Figure 1, of the drawings, is a plan view of our device, and

Figures 2 and 3 are details.

Our invention has relation to latches for doors and gates; and

It consists mainly in the arrangement of double catches, one of which is loose, and the other stationary, with a swinging guard or lock, all adjusted in such manner that the double catches are adapted to doors opening either to the right or left, and the latch in either case held firmly.

The letter *a* of the drawings represents a plate of metal, adapted for fastening to the door-jamb, by means of screws *b*.

The letter *c* is a catch, firmly attached to the plate *a*, and letter *d* is the latch.

The letter *s* is a slot, cut in the plate, and extending downward to a point immediately opposite the upper end of the latch, when in its place.

In the slot *s*, I adjust the catch *u*, in such manner that said catch may be moved upward or downward at will, the lower end of said catch being turned outward to the right and left, on the lower side of the plate, in such manner that the catch shall be held in the slot securely, and at the same time be allowed to slide up and down.

The letter *v* is a guard or lock, pivoted on the plate *A*, as shown. It is formed in the shape of an elbow,

and is swung back and forth, like the pendulum of a clock.

Our device is operated as follows:

The plate *a* is attached to the jamb of the door, and the latch on the door itself, or they may be reversed, and the latch placed upon the jamb.

To close the door and fasten it, we raise the catch *u*, and allow the latch to fall into its place in catch *c*. We then let go the catch *u*, which falls down, forming a shoulder over the latch, while the guard *v* swings to a perpendicular position, with its elbow resting upon the upper side of catch *u*, and thereby locking the latch securely.

The foregoing represents the operation of our device, when applied to a door opening towards the right.

When placed upon a door opening to the left, the catch *u* is moved upward, instead of downward, and the guard adjusted in its place under the same.

When the door is to be unfastened, the catch *u* is raised or lowered, as the case may require, and the elbow of the guard placed under the catch *u*, to hold it in the desired position above the latch, and thereby allowing said latch to be removed from the shoulder of catch *c*.

What we claim as our invention, and desire to secure by Letters Patent, is—

The combination and arrangement of the plate *a* with its slot *s*, catches *c* and *u*, and guard *v*, when constructed substantially as and for the purposes specified.

In testimony that we claim the above, we have hereunto subscribed our names, in the presence of two witnesses.

JOSEPH C. CURRYER.
WILLIAM C. YOUNG.
